UNITED STATES PATENT OFFICE.

HOWARD R. HUGHES, OF HOUSTON, TEXAS.

ROTARY BORING-DRILL.

1,316,094.

Specification of Letters Patent. Patented Sept. 16, 1919.

Application filed March 30, 1918. Serial No. 225,664.

To all whom it may concern:

Be it known that I, HOWARD R. HUGHES, a citizen of the United States, residing at Houston, Harris county, Texas, have invented a certain new and useful Improvement in 5 Rotary Boring-Drills, of which the following is a full, clear, and exact description, such as will enable others skilled in the art to which it appertains to make and use the 10 same.

This invention relates to drills of the type used in drilling wells in earth or rock, and more particularly to rotary drills for attachment to the end of a rotary drill stem for 15 use in drilling oil or water wells and the like.

One object of my invention is to provide a drill of the rotary type wherein the head of the bit is divided longitudinally along 20 the median line thereof, and in which the shafts upon which the rotatable cutters are mounted are integral with the two lateral sections of the head itself.

Another object is to provide, in a bit of 25 the kind described, a central web adapted to fit between the two longitudinal side pieces and interlock with the same, and to furnish a support for the interior end of the shafts upon which the cutters are mounted.

Another object is to provide channels in 30 the head of the bit which shall direct the water upon the cutters and on the material being drilled, in an especially efficient manner.

Another object is to construct a bit of extreme simplicity and in which each cutter 35 will be closely housed around its upper portion, to prevent accumulation of material on said cutters.

Other objects of my invention will more 40 clearly appear in the specification which follows and will be pointed out with more particularity in the claims appended hereto.

Referring to the drawing in which like 45 characters of reference refer to like parts throughout the different views:

Figure 1 is a side view of my improvement partly in section on the line 1—1 of Fig. 4;

Fig. 2 is a bottom plan view partly in section on the line 2—2 of Fig. 1;

Fig. 3 is a top plan view thereof; and

Fig. 4 is an interior side view of one of

the longitudinal sections of the head, showing one of the cutters in operating position. 55

Fig. 5 is a side view of the T-web removed.

Figs. 6 and 7 are views similar to Fig. 1, showing modifications in the shape of the web constructed to accommodate cutters set 60 at an angle.

Fig. 8 is a view similar to Fig. 1, showing a modified form of T-web and cutter mounting, one side being in section on the line 8—8 of Fig. 10. 65

Fig. 9 is a lower plan view partly in section on line 9—9 of Fig. 8.

Fig. 10 is an inner, side view of one of the parts of the head shown in Fig. 8.

Fig. 11 is an upper plan view of this embodiment of my invention. 70

Figs. 12 and 13 are views similar to Fig. 1 showing modified forms of T-web.

Fig. 14 is a diagrammatical plan view of the cutters shown in Fig. 12 illustrating the 75 manner in which the cutters contact with each other on the line of their beveled hubs.

Referring with more particularity to Figs. 1 to 5 inclusive, of the drawings, the head of my bit is composed of two longitudinal side 80 sections 6, making up the body of the head and interfitting to form a threaded upper shank 7, for attachment to the rotary drill stem, not shown. Between the two side members, 6, and extending approximately 85

half-way from the lower to the upper end of the bit, is a central T-web 8, having the upper end 9 extended laterally to fit within a groove 10, in each of the longitudinal side members. In each side of the web 8 adjacent the lower end of the same, and offset 90

slightly from each other, is a cylindrical recess 11, extending approximately half-way through the web. These recesses furnish supports for the two offset bearing shafts 13, 95

integral with the two side members 6. Each of the two members 6 of the head are further recessed on their inner faces at the lower end thereof, at 12, to accommodate a disk shaped cutter 14, toothed as at 15 for 100

the cutting operation.

These cutters, as previously mentioned, are offset from each other in such manner that one of them projects laterally from the head on one side of the bit, while the other 105 one projects from the opposite side of the

head, after the manner usual in this type of bit. Each of these cutters is furnished with a bushing 17, which is extended radially outward on the outer side of the disk 5 to form a combined bushing and washer for the cutter. On the inner side of the disk is an ordinary washer 16 furnishing an anti-friction contact on its inner face. Each of these parts of the bearing are made non-rotatable by means of a small dowel pin 18, passing through the periphery of the washers and interfitting with the adjacent part 10 of the head. The inner web 7 is more firmly attached in its registered position by means 15 of dowel pins 19, which fit within the head of the web, and also in holes 20 in the side members 6 of the head.

To lock the two side members 6 in co-operative relation with the inner web 8, under ordinary circumstances, the threading of 20 the shank 7 into the drill stem is sufficient. I have, however, provided a further locking means for use when convenient, consisting of two locking pins 21. These pins are seated 25 on opposite edges of the T-web 8 and extend in a position parallel to the adjacent disks in such a manner as to fit within a groove on the upper part of the shafts 13, as shown clearly in Fig. 1. Thus when the 30 locking pins 21 are inserted into the head, they will fit within holes in the web 8 and by passing through the groove in the upper part of each of the shafts 13, a lateral movement 35 of the shaft will be prevented, in this way materially strengthening the lower part of the head.

The lower end of the web 8 is grooved in a direction parallel to the cutters to furnish 40 a cutting or crushing surface 23 adapted to disintegrate any core left standing in the center of the holes, untouched by the cutters. Each outer side of this lower surface is also 45 beveled off as at 22 to allow all possible freedom for the washing away of the disintegrated material.

On the upper end of the threaded shank of the drill bit, I have provided a threaded nipple 25 for the attachment of a lubricating cylinder, not shown. Passing downwardly 50 from the upper end of this nipple 25 are two inclined oil ducts 26, connecting the lubricator with the vertical oil ducts 27 by means of which the lubricating fluid is conducted to the bearing of the cutters 14, as shown.

55 In this bit, as is usual with rotary drills, provision is made for conducting the flushing water from the interior of the hollow drill stem downward through the head of the bit so as to flush away the material disintegrated by the action of the drill.

In my improvement, I have formed the water ducts so that the water shall issue on a line diametrical to the disk shaped cutter, the housing of the cutter being also constructed so that the point where the water

issues into the cutter slot, will be approximately midway between the outer edges of said housing. This structure has certain advantages. By striking the cutter diametrically the water tends to better loosen 70 any material which may be clinging thereto, and force the same laterally from the housing 12. The distance being equal, or approximately so, toward each side of the slot, the water will be projected forcibly both 75 from the front and rear of the cutter.

A channel for the flushing water is formed in each of the two interfitting side members 6 as shown particularly in Figs. 3 and 11. These channels conduct the water to the cutter in the manner described.

The channel in that portion of the head through which the web 8 extends, is formed by the cutting of a groove in the side of the web 8 and a registering groove in the interior side of the co-operating part 6. As will be seen in dotted lines in Fig. 1, the groove in the part 6 ends at the upper side of the slot 12 in which the disk is mounted, but the groove in the outer face of the web 8 extends in a direction inclined backwardly from this point along the face of the slot and issues in an outwardly directed groove at the base thereof, as shown at 29 in Figs. 2 and 5. This outward inclination of the channel toward the base of the head is partly for the purpose of directing the water laterally along the disk and also to avoid contact with the washer 16 of the disk. As the cutters rotate in a clockwise direction, as seen 100 in Figs. 4 and 8, the natural tendency would be for the cutter to carry a somewhat larger portion of the water in the direction of rotation of the cutter but by the backward inclination of this water duct on the surface of 105 the web this tendency is overcome to a great degree. This tendency of the water to follow the direction of rotation of the cutter is also partly overcome by the backward inclination of the teeth on the periphery of the 110 cutter as indicated in Figs. 1 and 4.

In the assembling of my improved drill bit, one of the lateral members 6 is first provided with the portion 17 of the bushing fitting over the cutter shaft 13 and over this bushing is fitted the disk 14, the two parts of the bushing being locked in place by means of dowel pins 18. The view shown in Fig. 4 will illustrate this much of the assembly of the bit, with the exception of 120 the washer 16. The T-web 8 is then fitted over the end of a shaft 13, the dowel pin 19 fitting within the hole 20 of the side member 6. The disk on the opposite side is then arranged upon the shaft 13 in the manner 125 previously described, and the two parts of the head are then fitted together in registered position, as shown in Fig. 1. The pins 21 are then fitted in place and the drill is ready for attachment to the drill stem.

- In the rotation of the bit in the usual clockwise direction, the cutting disks 14 will serve to shear away the material from the side and bottom of the hole, and the action of the toothed periphery thereof will assist in disintegrating the cutting so that they may be flushed back upward to the surface by means of the water issuing from the channels 28 of the head. The cutting disks are housed somewhat in the head as previously described, but the slot to the rear of the cutter has been left open as shown at 24 to allow a free outward movement of the disintegrated material, both to the front and rear of the cutter with approximately equal volume, the slot being kept open by the force of the flushing water impinging upon the teeth of the cutting disk, and directed laterally from the housing.
- In Figs. 5 and 6, I have shown the cutters set at an angle to the longitudinal axis of the head and the shape of the T-web is modified to accommodate this arrangement. In Fig. 5 the cutters are arranged to incline inwardly toward the bottom and in Fig. 6 the cutters are inclined inwardly toward the top. These different arrangements of the cutters are not thought to be new. In order to accommodate my improvement to such inclined positions of the cutters, however, I have had to incline the integral cutter shafts from the horizontal. In Fig. 5 the shafts 13' are inclined upwardly making it necessary to provide an inclined recess 11' in the lower part of the T-web 9' to receive the shaft 13'. The T-web is also beveled on each side at 30, parallel to the cutter, thus forming one wall of the recess 12' of the cutter housing, the other wall being formed by the inner face of the head.
- The upper and lower walls of the groove 10' are also inclined in parallelism with the cutter shaft for purposes of assembly, the parts being compelled to move together parallel with the inclined shaft 13'.
- In Fig. 6 the cutter bearing shafts 13'' are inclined downwardly and the walls of the slot 10'' are inclined parallel to the shaft.
- The T-web 9'' is beveled outwardly toward the base to closely house the cutters in the usual manner. The assembly of the bit, when these modifications are used, is practically the same as in that of my preferred embodiment shown in Fig. 1. The principal difference lies in fitting the two parts 6 of the head onto the web as it is necessary to move the side parts with a motion parallel to the inclined cutter shafts.
- In Figs. 8 to 13, inclusive, I have shown my divided head bit provided with a special form of cutter which serves to nearly enclose the shaft and bushing on which it is mounted. In Figs. 8 to 11 these cutters 14^x are erect and the shafts are horizontal. The cutters are offset as in the other forms but the inner hub of each cutter is closed, enlarged and flattened to form a smooth surface for contact with the other cutter. The cutter hubs contact for a part of their width, as shown at 32 in Fig. 9, and any lateral movement of the cutters toward each other is thereby prevented. In this arrangement, when the bit is assembled, no locking nuts for the cutters are necessary, and the entrance of sand or other material to the bearing is largely avoided. On the inner end of the recess 11^x into which the shaft fits, is a small conical counterbore 33 acting as a cup for oil accumulating about the bearing. No inner washer is necessary in this form of cutter.
- In order that the cutters shall be closely housed around their upper portions, thus to prevent accumulations of material around the cutters, the T-web 8^x may be fitted in the head between the cutters in the manner described in relation to the modifications set forth in Figs. 1 to 7. The web does not extend down to support the cutters in this form, however, but is shaped to fit the inner contour of the cutters and close up the space as is clearly shown in Fig. 8. If desired the T-web may be omitted altogether in this modification. The water channels in this modification are directed from the upper end of each part diametrically toward the axis of the cutters but are not open along the lower end of the bit in the T-web. The said web does not extend below the cutters. As a result the water is projected nearly equally both from the front and rear of the cutter housing. The tendency of the water to follow the direction of rotation of the cutter is partially overcome here as well as in the other forms by the inclination of the cutter teeth toward the rear.
- In Figs. 12 and 13 the cutters are inclined from the longitudinal axis of the head as in Figs. 5 and 6. The inner hubs 110 of the cutter are beveled as at 34 in each case at the point of contact of the offset cutters to allow for this inclination thus allowing free rotation of the same.
- The web 8^y in Fig. 12 is similar to the web in Fig. 8 but is widened to fit the larger space between the upper portions of the cutters. In the embodiment of my invention shown in Fig. 13 the web is extended below the cutter shafts as in Figs. 1 to 7, inclusive. This illustrates how the web may be adapted with the closed hub form of cutter to more closely house the cutters and to even support the inner hubs of the cutters. The lubrication and bearing means is the same in all the modifications and need not be further described.
- The advantages of my improvement lie mainly in the ease of assembling of the parts of my drill head, and also in the strength 130

of the same. Owing to the fact that I have a central removable web, it is possible to make the shafts integral with the head and still to provide a central support for the shafts when it is considered necessary. By making the shafts integral with the parts of the head, the disadvantages of the separate shaft and locking nuts are entirely avoided. Thus with my improved structure, when assembled, there is no part which can be easily lost in the hole. Each part interfits in such a manner that there is no possibility of a loosening of the operating parts. Furthermore, when the head is removed from the well for the purpose of inserting new cutters upon the head to replace those which have become worn, the drill is removed from the drill stem and the pins 21 extracted, if the same are used, and the cutters are then instantly accessible. The usual difficulties attending the removal of the disks from the head are thus practically avoided. In the embodiment shown in Figs. 8 to 13, inclusive, wherein the closed hub form of cutter 26 is used, the length of the head is somewhat reduced thus making it possible to bind the parts firmly together when the head is screwed into the drill stem without the assistance of additional fastening bolts or screws. The T-web may be extended to close the lower part of the head between the cutters and also serve as a support for the hubs of the cutters or the web may simply close the housing between the upper portions of the cutters as in Figs. 8 to 12, inclusive. I have shown my invention applied to a disk bit, but it will be possible, of course, to apply it to other forms of bit without departing materially from the spirit of my invention.

Having thus described my invention, what I claim as new and desire to protect by Letters Patent, is:

1. A bit for well drilling, comprising a head divided longitudinally into two sections, each of said sections being recessed on its inner surface for approximately half its length, a T-shaped web in said recess, and cutters supported between said web and side sections.

2. In a bit for well drilling, a head longitudinally divided into two side sections, said sections being recessed on the lower inner faces thereof, a T-shaped web in said recesses, and cutters mounted in said head.

3. A bit for well drilling, comprising a head divided longitudinally into two sections, each section being recessed on its inner face for a portion of its length, a T-web in said recesses, a shaft on each side section supported in said web and cutters on said shafts.

4. A bit for well drilling comprising a head divided longitudinally into two equal sections, the contacting inner faces of which

are recessed to receive a T-web, an inwardly projecting cutter shaft integral with the lower end of each section, said shaft being adapted to fit within a recess in the said T-web and be supported thereby.

5. In a drill bit, a longitudinally divided head, a central T-shaped web fitting in the lower portion thereof, cutter shafts integral with the head and adapted to be supported in said web.

6. In a drill bit, a longitudinally divided head, a central T-shaped web fitting in the lower portion thereof, cutter shafts integral with the head and adapted to be supported in said web and locking pins engaging said web and shafts to maintain the parts in assembled position.

7. In a drill bit a longitudinally divided head, a central T-shaped web fitting removably in the lower portion thereof for the purpose described, and cutters supported by said web and said head.

8. In a drill bit, a head split longitudinally into two sections each of which is recessed on the lower portion thereof and provided with an integral cutter shaft, and a T-web fitting within said recess and serving to support said shafts.

9. A split head for well drills composed of two longitudinally divided sections, cutters mounted rotatably thereon and a central T-shaped web extending from the cutters approximately half the length of the head, and means to lock the said sections in assembled position.

10. A split head for well drills composed of two longitudinal sections and a central T-shaped web shorter than the two said sections and fitting within a recess in the lower part of said sections, and integral cutter shafts on said sections.

11. In a drill bit, a longitudinally divided head, offset rotary cutters on the lower end thereof, shafts for said cutters integral with said head, and an inner removable support for said cutters.

12. In a drill bit, a longitudinally divided head, rotary cutters pivoted at the lower end thereof, pivot shafts for said cutters integral with a part of said head, a central support for said shafts, means to connect said shafts to said support, bushings for said cutters and locking means for said bushings.

13. A split head for well drills comprising two longitudinal side sections and a central T-shaped web fitting within a recess in the lower part of said sections, said web being beveled on its opposite sides to form a wall for inclined cutter slots and cutter shafts on said sections.

14. In a drill bit, a head, cutters mounted in offset relation in slots in the lower part thereof, water channels in said head adapted to project flushing water diametrically to said cutters, said channels delivering water

to said slots midway between the outer margins thereof.

15. In a drill bit, a head longitudinally divided into two sections, a central web between the said sections, cutters mounted in slots in the base of said head, water channels in said head formed by coöperating grooves in the sides of said sections and said web, the groove in said sections terminating in 10 said slots, the groove in said web being directed backwardly from the top of said slots and terminating at the base of the slots.

16. In a drill bit, a head, offset cutters housed therein, the housing being higher on 15 the forward than on the rearward side, water channels in said head directing the

water diametrically to said cutters, at a point midway of said housing, and teeth on said cutters inclined backwardly from the point of projection of the water upon the 20 same.

17. In a drill bit, a head for the support of rotary drilling cutters, said head comprising two registering side sections each having a cutter shaft thereon and recessed 25 on their meeting faces for approximately one-half their length, and a T-shaped supporting web in said recess designed to assist in the support of the cutters.

In testimony whereof, I hereunto affix my 30 signature this the 25 day of March, 1918.

HOWARD R. HUGHES.
